M. H. AVED.
INVISIBLE SUSPENDERS
APPLICATION FILED AUG. 13, 1919.

1,356,955.

Patented Oct. 26, 1920.

UNITED STATES PATENT OFFICE.

MAURICE H. AVED, OF HARVEY, NORTH DAKOTA.

INVISIBLE SUSPENDERS.

1,356,955.

Specification of Letters Patent. Patented Oct. 26, 1920.

Application filed August 13, 1919. Serial No. 317,189.

To all whom it may concern:

Be it known that I, MAURICE H. AVED, a citizen of the United States, residing at Harvey, in the county of Wells and State 5 of North Dakota, have invented certain new and useful Improvements in Invisible Suspenders, of which the following is a specification, reference being had to the accompanying drawings.

10 This invention relates to invisible suspenders, as they are termed, and particularly to improvements on the suspender or garment supporter illustrated in my Patent, No. 1,298,274, granted on March 25, 1919.

15 The general object of the invention is to provide a garment supporter or suspender of that type known as invisible, that is in which the suspenders are completely concealed by the shirt, wherein the use of metal 20 clasps or yokes is minimized, and wherein the straps of which the supporter or suspender is composed have a maximum freedom of movement at the back to accommodate and permit the free movement of the 25 wearer's shoulders.

A further object is to provide a suspender or garment supporter of this type wherein the two shoulder webs or straps have a "back slide" or connection with each other, and wherein the ends of the two webs are connected by straps having sliding engagement 30 with each other to thereby give that freedom of motion necessary for comfort and ease to the wearer and to give freedom of movement 35 at the back to compensate for the movements of the shoulders of the wearer and adjust themselves to persons who are long-waisted or short-waisted.

40 A further object is to form the back slide of a supporter of non-elastic webbing to thereby permit a better sliding movement of the webs upon each other, thus giving more freedom of movement to the person and more comfort to the body.

45 Other objects will appear in the course of the following description.

My invention is illustrated in the accompanying drawings, wherein:

Figure 1 is a perspective view of the suspenders;

Fig. 2 is a detail view of the back slide.

Referring to the drawings, it will be seen that my improved garment supporter comprises two straps 10 and 10^a, which are relatively broad, and formed of elastic material, each of these sections 10 at its lower end be-

ing passed through a yoke 11 and then extending upward to an adjusting buckle 12. At its upper end, each of the members 10 is provided with a yoke 13 and through this 60 yoke there is disposed an elongated loop 14 of flat, non-elastic webbing, this loop being preferably, however, of a single piece of material stitched at 15. It will be seen that the yoke 14 has freedom of movement in the 65 yoke 13. One thickness or strand of one loop passes between the two thicknesses of the other loop, as shown in Fig. 2, so that while these two loops 14 are interconnected with each other, yet they may shift readily 70 with relation to each other. The webbing section 10 carries at one end the yoke 11, as previously stated, and through the eye of this yoke is disposed the elongated looped parts formed of a non-elastic, textile band 17. 75 Said band is in the form of an elongated loop and is threaded through the yoke 11, through the yoke 16, and through a yoke 18 engaging with a button clip 19 of conventional form. It will be seen from Fig. 1 that the inner 80 and outer strands of the loop 17 have free sliding motion in the yoke 18, which is provided with transverse rollers to that end so that this yoke can move freely and so that if the yoke 18 is given a sidewise pull, one 85 of the divergent branches of the loop 17 will shorten and the other correspondingly lengthen. The loop 17 is connected to a section of elastic webbing 20 which, in turn, is connected to the corresponding loop 14. Of 90 course, the webbing 10^a is also connected to a loop 17 carrying the yoke 18 in the same manner as before described, and this loop is also connected to a webbing section 20^a engaged in the loop 14.

95 This device is intended to be disposed with the portions 10 and 10^a extending over the shoulders of the wearer and with the back slide, composed of the two loops 14, on the back of the wearer. It will be obvious that this garment supporter permits both back slip or slide and side slip or slide which effectively distributes the weight of the trousers or other garment on the two bands 17. This garment supporter prevents the 100 body garment from bulging out either at the front or back and causes the garment to hang properly on the wearer. The device may be applied with facility and is adapted to be disposed underneath the shirt so that the 110 supporter will be invisible. The general convenience of a supporter of this kind is

recognized. The specific improvements over the supporter shown in my prior patent consist in the use of material which is non-elastic in order to form the back slide, in other words in the use of non-elastic material to form the loops 14. I have found in practice that the elastic material tends to stick or impede free movement, while non-elastic material, such as that used to form the webs or loops 14, does not tend to stick but the plies of the loops move freely over each other with the movement of the shoulders, thus giving greater freedom of movement and more comfort to the wearer.

Furthermore, it is pointed out that these loops 14 are free to move within the yokes 13 so as to permit of much greater freedom of movement than would be possible if these yokes 13 were engaged with the loops by stitching. One of the most important things in this connection is the provision of a back slide constructed in accordance with my invention, with the side slides formed of the loops 17. This is absolutely necessary to give full freedom of motion and comfort and ease to the wearer, to cause the suspenders to conform to every movement of the shoulders, and to adjust themselves to different waists of persons, whether the person be long or short-waisted or medium-waisted. This is absolutely necessary in invisible supporters, because where there are only two points of suspension, it is necessary to obtain freedom of movement so as to properly adjust the weight of the trousers to keep them from bulging out and to take off strain from the shoulders. Invisible supporters which do not have perfect freedom of movement at the back where the webs cross each other, are uncomfortable and prevent proper hang of the trousers on the body.

I claim:—

1. A garment supporter composed of two bands of elastic webbing, each band being composed of two sections of elastic webbing spaced from each other, an elongated loop of non-elastic webbing separate from but connected to and connecting said sections, the loop of one band crossing and passing through the loop of the other band, and the two loops having free, sliding engagement with each other, and loops of non-elastic ma-

terial each having engagement with the forward end of one of said bands and the rear end of the other band, and garment engaging devices slidably mounted on said last named loops. 55

2. A garment supporter composed of two bands of webbing, each band being composed of two sections of webbing spaced from each other, an elongated loop of webbing separate from and disposed between the two first named sections, yokes having eyes with which the adjacent ends of the first named sections are connected and having eyes through which the said loop loosely passes, the loop of one band crossing and passing through the loop of the other band and the two loops having free sliding engagement with each other, and loops of material each having engagement with the forward end of one of said bands and the rear end of the other band, and garment engaging devices slidably mounted on said last named loops. 65 70 75

3. A garment supporter comprising two bands adapted to be disposed over the shoulders of the wearer, each of said bands being composed of two sections, one of said sections adapted to extend over the shoulders 80 of the wearer and down on the front of the body, the other section extending downward over the back of the body, the two sections being joined by a loop of non-elastic material, one strand of the loop of one band 85 being passed between the strands of the loop on the other band, whereby said loops have free, sliding engagement with each other, each loop being connected to the shoulder section of the corresponding band by a yoke 90 and having an eye through which the loop slidably passes, the forward end of each shoulder band having a yoke formed with an eye and the lower end of each back section being formed with an eye, a loop of non-elastic material passed through the eye on the yoke of each shoulder section and through the eye on the yoke of the opposite back section, and a garment engaging device 95 slidably engaged with said last named loops. 100

In testimony whereof I hereunto affix my signature.

MAURICE H. AVED.
